UNITED STATES PATENT OFFICE.

HARRY ALVIN MICHAEL, OF BEAVER FALLS, PENNSYLVANIA.

PIPE-WRENCH.

1,311,610.

Specification of Letters Patent. Patented July 29, 1919.

Application filed September 19, 1918. Serial No. 254,792.

To all whom it may concern:

Be it known that I, HARRY ALVIN MICHAEL, a citizen of the United States, residing at Beaver Falls, in the county of Beaver and 5 State of Pennsylvania, have invented a new and useful Pipe-Wrench, of which the following is a specification.

This invention has reference to pipe wrenches, and its object is to provide a wrench of the same general character as 10 that shown and described in Letters Patent No. 764,619, granted to J. C. McQuilkin on July 12, 1904, for a pipe wrench, of which patent I am the sole owner.

15 A large number of wrenches made in accordance with the said Letters Patent was placed upon the market but after extended use the patented wrench was found to be constructively defective. Ultimately, however, I succeeded in devising the wrench herein shown and described, in which wrench the shortcomings of the patented wrench 20 have been overcome.

In accordance with the invention the 25 wrench is provided with a screw stem pivoted at one end to the wrench handle near one end of the latter and held to the screw stem by an adjusting nut is one end of the shank of one jaw of the wrench, the other 30 jaw being mounted in the handle portion of the wrench near the pivotal support of the screw stem. A spring within the handle of the wrench, which handle is made hollow, is located to act upon the rear face of the 35 shank of the movable jaw so as to yieldably maintain the movable jaw in a forward position. When the jaws of the wrench are applied to a pipe or other part to be turned the movable jaw rocks on a pivot eccentric 40 to the pipe in a manner to clamp the pipe between the two jaws. When, however, it is desired to loosen the wrench from the pipe the slightest movement in the reverse direction to the movement of the wrench in turning 45 the pipe immediately loosens the wrench from the pipe no matter how tightly the wrench may have previously gripped the pipe.

The construction of the wrench admits of 50 its manufacture in large part of sheet metal of suitable gage bent into shape while the jaws and parts immediately associated therewith may be made of steel forgings.

The invention will be best understood

from a consideration of the following detailed description taken in connection with the accompanying drawing forming part of this specification, with the understanding, however, that the invention is not confined to any strict conformity with the showing of the drawing but may be changed and modified so long as such changes and modifications mark no material departure from the salient features of the invention as expressed in the appended claims.

In the drawing:—

Figure 1 is an elevation of a wrench constructed in accordance with the invention.

Fig. 2 is a longitudinal section thereof with the parts in a position which may be assumed in grasping a pipe.

Fig. 3 is a front elevation of the wrench.

Fig. 4 is a section on the line 4—4 of Fig. 1.

In the drawing, there is shown a handle or 75 body member 1 with a handhold portion 2. The handle as a whole may be made of sheet metal of suitable gage bent into shape, a convenient cross sectional form being that of a flat ellipse, as indicated in the drawing 80 particularly in Fig. 4. At one end the handle member 1 is expanded laterally into wings substantially parallel one with the other and constituting the head 3 of the handle of the wrench. Between the head end 3 85 and the handhold 2 that side of the handle corresponding to the projection of the head 3 is cut away for a distance lengthwise of the handle to form a slot 4 to accommodate certain parts to be described.

The wings of the head 3 are recessed, with 90 the bottom of the recesses, indicated at 5, at a slight angle to a perpendicular to the longitudinal center line of the wrench handle and the inner end of each recess 5 is undercut, as shown at 6, to receive the beveled end 7 of the stationary jaw 8 of the wrench, this stationary jaw having the usual teeth 9 and a central longitudinal lug 10 for insertion 95 between the wings of the head 3, the jaw 100 being held in its seated position by a rivet 11 or other fastening means traversing it. In this respect the wrench may be similar to other pipe wrenches.

There is also provided a movable jaw 12 105 having gripping teeth 13 as is customary and the jaw 12 is provided with a stem 14 which, when the parts are assembled, enters

the handle 1 through the head end, the handle being hollow and extends through the handle to near that end of the slot 4 toward the handhold 2. The stem is formed on the 5 end remote from the head 12 with a laterally projecting lug 15 having a passage 16 therethrough lengthwise of the stem 14. Spaced away from the lug 15 the stem 14, on the same side of it as the lug, is provided with a 10 projecting shoulder 17.

Pivoted between the wings of the head 3 by means of a pivot pin 18 is a block 19 formed at one end of a screw stem 20, which stem traverses a nut 21 mounted between the 15 lug 15 and shoulder 17, the stem 20 traversing the passage 16. The screw stem 20 constitutes a connection between the head 3 of the wrench and the movable jaw by way of the nut 21 which is confined by the lug 15 20 and shoulder 17 so that on turning the nut the movable jaw may be caused to travel toward and from the fixed jaw, these parts being generally similar to the arrangement shown in the aforesaid Letters Patent.

Fast to the handle 1 within the latter is a spring 22, which may be in the form of a leaf spring, and is located at the back of the handle so as to bear against the stem 14 at the rear face thereof, thus urging the 25 stem toward the fixed jaw, the free end of the spring being close to the head end of the handle 1. The result is that the movable head 12 is constantly urged toward the jaw 8 about the axis of the pivot 18, causing the lug 15 to move toward the handle 1. This will normally hold the teeth 9 and 13 30 of the two jaws in substantially parallel relation. If, now, the movable jaw be propelled by the nut 21 to a sufficient distance 35 away from the fixed jaw to admit the application of the wrench to a pipe 23 and force be applied to the handle of the wrench 40 to turn the pipe, as for instance, if the wrench as viewed in Figs. 1 and 2 be turned 45 counter-clockwise, the jaws will grip the pipe in a manner to unscrew, providing the pipe is furnished with right hand threads. In applying the wrench the tendency 50 is to tilt the movable jaw 12 away from the fixed jaw 10 in opposition to the normal tendency of the spring 22, thus 55 allowing the pipe to seat between the jaws, Fig. 2 showing the position of parts somewhat exaggerated. In applying a turning 60 force to the wrench the movable jaw travels over the fixed jaw about the axis of the pivot 18 and thereby brings the movable jaw 12 into firm gripping engagement with the pipe, forcing the latter against the fixed jaw 8 and the teeth on the two jaws so firmly 65 grip the pipe that the latter is constrained to turn with the wrench. As the turning force is applied the screw stem 20, lug 15 and nut 21 move toward the handle 1 to a position somewhere between the positions shown

in Figs. 1 and 2 and until the pipe is as firmly gripped as may be.

With the wrench disclosed in the aforesaid Letters Patent a spring was applied between the fixed jaw and the stem of the movable jaw with the result that the spring tended to throw the stem of the movable jaw toward the rear wall of the handle. With the wrench of this invention the spring is located between the rear edge or 75 face of the stem or shank 14 and the inner rear face of the handle 1 with the spring acting against the shank 14 at a point closer to the corresponding end of the handle than the pivot 18 about which the jaw 12 rocks. 80 The result is that the normal tendency of the spring 22 is to force the jaw 12 forwardly and thereby hold it and consequently when the wrench is applied to a pipe or other part to be turned the jaw 12 is forced 85 rearwardly until the parts are properly gripped. Now, when it is desired to release the wrench from the pipe it requires but a slight reverse movement of the wrench to cause the movable jaw to rock away from 90 the fixed jaw, thereby enlarging the space between the two jaws and letting go the grip on the pipe; whereby the wrench is at once released from the pipe.

What is claimed is:—

1. A pipe wrench comprising a handle, a jaw fixed thereto, another jaw associated with the first-named jaw and provided with a shank, an adjusting screw pivoted to the jaw end of the handle and extending away 95 therefrom and connected to the shank of the movable jaw to constitute a support and pivot for said movable jaw, and a spring on the handle engaging the rear of the shank of the movable jaw at a point closer to the 100 jaw-carrying end of the handle than the pivot end of the adjusting screw.

2. A pipe wrench comprising a handle member, a fixed jaw mounted in the handle member, a movable jaw associated with the 110 fixed jaw and provided with a shank movable into and out of the handle member in the direction of both the shank and handle member, an adjusting screw pivotally mounted in the handle member and supporting 115 and constituting the pivotal support for the movable jaw, and a spring carried by the handle member and engaging the shank of the movable jaw on the side thereof remote from the pivot support of the movable jaw. 120

3. A pipe wrench comprising a handle member of sheet metal bent into shape with a head formed of oppositely disposed wings and the side of the handle where provided with the wings cut away to form a longitudinal slot, a jaw fixed between the wings, an adjusting screw pivotally mounted between the wings and extending along the slotted portion of the handle, a movable jaw associated with the first-named jaw and 125 130

having an elongated shank with a lug traversed by the adjusting screw and a shoulder spaced from said lug, an adjusting nut on the screw located between the lug and 5 shoulder, and a spring fast to the handle within the latter on the side thereof remote from the adjusting screw and extended toward the head end of the handle and there bearing against the shank, whereby to normally force the shank and jaw carried thereby toward the fixed jaw.

In testimony that I claim the foregoing as my own, I have hereto affixed my signature.

HARRY ALVIN MICHAEL.
